A detailed cross-sectional diagram of a circular device, possibly a lens or filter. The diagram shows a multi-layered structure with various internal components. Labels are present around the perimeter and within the central cavity. Labels include: 39, 38, 37, 35, 34, 31, 30, 29, 28, 27, 26, 25, 24, 23, 22, 21, 20, 19, 18, 17, 16, 15, 14, 13, 12, 11, 10, 9, 8, 7, 6, 5, 4, 3, 2, 1, and 0. The diagram is highly detailed, showing internal structures like a central stop, a diaphragm, and various coatings or filters.

UNITED STATES PATENT OFFICE.

WALTER PORANSKI, OF CHICAGO, ILLINOIS, ASSIGNOR TO NATIONAL TRADING CO.,
OF CHICAGO, ILLINOIS, A CORPORATION OF OHIO.

VANITY CASE.

Application filed February 5, 1926. Serial No. 86,315.

My invention relates to vanity cases and has among its other objects the production of devices of the kind described which are extremely neat and attractive in appearance, 5 convenient, durable, compact, and are quickly and easily refilled.

A particular object of the invention is to provide devices of the kind described having improved means for mounting mirrors 10 therein.

Another particular object of the invention is to provide devices of the kind described having improved means for holding powder, rouge or the like.

One form of the invention is embodied in 15 a vanity case comprising a box for holding powder, a cake of rouge being held in a lid hinged to the box. The rouge is retained in place in the lid by a ring frictionally engaging an upstanding flange carried by the lid. A mirror is pivoted upon a bent wire 20 which has its ends pivoted in the ring, the mirror and bent wire being constructed to fold back into the lid when not in use. If 25 the mirror, the bent wire and the ring are removed from the flange as a unit a fresh cake of rouge may be inserted in the annular flange. When the ring is replaced the rouge is securely held against accidental displacement 30 relative to the lid and may be concealed beneath the mirror when the vanity case is opened.

Many other objects and advantages of the 35 construction herein shown and described will be obvious to those skilled in the art from the disclosure herein given.

To this end my invention consists in the 40 novel construction, arrangement and combination of parts herein shown and described, and more particularly pointed out in the 45 claims.

In the drawings, wherein like reference 50 characters indicate like or corresponding parts:

Fig. 1 is a view in elevation of a vanity 55 case embodying my invention, the vanity case being shown as it appears when open for use;

Fig. 2 is a section taken on line 2—2 of 60 Fig. 1; a mirror forming part of the improved vanity case being shown in a position wherein it permits access to a cake of rouge carried in the case;

Fig. 3 is a section taken on line 3—3 of 65 Fig. 1; and

Fig. 4 is a section taken on line 4—4 of 70 Fig. 2, a mirror carrying member being shown in a changed position.

In the drawings, I have illustrated a preferred form of the invention embodied in 75 a compact or vanity case, which preferably comprises two or more members hinged to each other. Thus, I preferably provide a box 10 having a lid 11 which is secured to the box by a hinge 12. In the illustrated 80 embodiment of the invention the box 10 is adapted to hold a quantity of finely divided powder which becomes a firm compact mass under pressure. The box 10 preferably 85 comprises a substantially cylindrical wall 14, a detachable back 15 and a perforate member 16, the back 15 being screw-threaded to the wall 14. The construction is such that the perforate member 16 may be rotated relative to the wall 14 to cause the powder to 90 be forced from the box 10 through the perforations of the member 16, the detachable back 15 being removed when the box is to be refilled with powder. The surface 18 of 95 the member 16 may be concave or otherwise adapted to accommodate a powder puff 19.

It is to be understood that I am limited to the above described details of construction only to the extent indicated in the appended claims, as, in some forms of the invention. I may prefer to provide a box 100 adapted to hold powder in cake or other form.

The lid 11 preferably comprises a top wall 105 20, the wall 20 being preferably formed with a concave inner surface as illustrated in Fig. 2. Preferably formed integral with the wall 20 is an integral cylindrical flange 22 adapted to engage a shoulder 24 formed upon the cylindrical wall 14. It will be 110 noted that the flange 22 telescopes over a portion of the cylindrical wall 14.

The lid is provided with means for holding a cake of rouge or the equivalent, the means preferably comprising a plate 25 positioned within the lid and centrally apertured so that an upstanding annular flange 115 27 may be provided to form a chamber 28 which accommodates a cake of rouge 29 carried by a dished disc 30 resting against the 120 inner surface of the wall 20. (See Figs. 2 125

and 4.) Obviously, I may dispense with the disc 30 if I so desire. The rouge 29 is held against lateral displacement by the flange 27 and is retained in the chamber 28 by a ring 34 hereinafter described.

An annular flange 33 is preferably formed at the outer edge of the plate 25 to frictionally engage the inner surface of the flange 22 so that the plate 25 may be readily secured 10 in the lid by pressing it into place.

The aforementioned ring 34 frictionally engages the outer surface of the upstanding annular flange 27 and is constructed with an inwardly extending flange 35 or the equivalent engageable with the marginal portions of the rouge 29 to prevent accidental displacement of the rouge relative to the lid. At one point the flange 35 is formed with a lug or lip 37 for holding a powder puff 38.

Carried by the ring 34 is a substantially U-shaped member 39 formed from a length of wire which has its end pivotally mounted in the ring 34 and deformed as at 40 to prevent withdrawal of the U-shaped member 25 from the ring. The annular flange 27 may be provided with slots 42 to accommodate the deformed ends of the U-shaped member 39.

Pivottally secured to the U-shaped member 39 intermediate its ends is a mirror frame 43 which comprises a back 44 or the equivalent formed with an eye 45, the eye 45 pivotally securing the frame 43 to the member 39. The back 44 cooperates with a bezel 47 to hold a mirror 48. A finger-piece or lug 49 is formed upon the bezel 47 and provides means whereby the mirror frame and mirror may be easily and quickly withdrawn from the lid 11, the construction of the member 39 and the mirror frame 43 being such that they may be brought into the positions wherein they are shown in dotted lines in Fig. 2. It will be noted that the member 39 is adapted to fit snugly around the ring 34 and that the mirror frame 43 may be inserted in the lid 11 in such manner that it will not interfere when the lid is brought into its closed position.

Fig. 2 illustrates one of the positions into which the mirror may be brought to make the rouge accessible to the user, the mirror being also conveniently disposed for the user. It may be mentioned that the rouge may be concealed beneath the mirror if the user so desires, the case being then opened to expose the surface 18 and the mirror as illustrated in Fig. 1.

The supply of rouge 29 may be readily renewed by first withdrawing the ring 34 from the annular flange 32. This is done by pulling upon the member 39 until the ring 34 slips off of the annular flange 27. The member 25 is not withdrawn from the lid 11 during this operation as the member 25 and

the lid 11 are so proportioned that there is a 65 tighter fit between them than there is between the annular flange 27 and the ring 34. After the ring 34 has been removed from the annular flange 32, a refill of rouge may be inserted in the annular flange 32, the ring 70 34 being then replaced upon the annular flange.

Having thus described my invention, it is 75 obvious that various immaterial modifications may be made in the same without departing from the spirit of my invention; hence I do not wish to be understood as limiting myself to the exact form, construction, arrangement and combination of parts herein shown and described or uses mentioned. 80

What I claim as new and desire to secure by Letters Patent is:

1. A vanity case comprising a box member, a lid member hinged to said box member, an annulus frictionally secured to said 85 lid member, a second annulus frictionally secured to said first-mentioned annulus for retaining a cake of powder therein, a mirror, and means carried by said second annulus for holding the mirror. 90

2. A vanity case comprising a box member, a lid member for said box member, an annulus frictionally secured to said lid member, a second annulus frictionally secured to said first-mentioned annulus for retaining a 95 cake of powder therein, a mirror, and means pivoted to said second annulus for holding the mirror.

3. A vanity case comprising a box member, a lid member hinged to said box member, an annulus frictionally engaging said lid member, a second annulus frictionally engaging said first-mentioned annulus for retaining a cake of powder therein, and means formed on said second annulus for holding a 100 powder puff. 105

4. A vanity case comprising a box member, a lid member hinged to said box member, an annulus frictionally secured to one of said members, and a second annulus frictionally secured to said first-mentioned annulus for holding powder therein. 110

5. A vanity case comprising a box member, a lid member hinged to said box member, an annulus frictionally secured to said lid member, a second annulus frictionally secured to said first-mentioned annulus to be quickly detachable therefrom, said first-mentioned annulus and said second-mentioned annulus being adapted to cooperate to hold a cake of powder, a member pivoted to said second annulus, a mirror pivoted to said pivoted member, and means formed on said second annulus for holding a powder puff. 115 120

In testimony whereof, I have hereunto 125 signed my name.

WALTER PORANSKI.
